GARMENT HANGER

Malcolm R. Ross, Macon, Ga.

Application October 3, 1936, Serial No. 103,932

6 Claims. (Cl. 211—181)

This invention relates to garment hangers and more particularly to a hanger of the display type which is adapted to support trousers or the like in a manner whereby individual trousers may be removed from the display rack without removal 5 of the supporting hanger.

An object of this invention is to provide a display rack for trousers which is so constructed that pairs of trousers may be supported from a pair of 10 horizontal supporting bars carried by a standard and a plurality of such horizontal bars may be secured to a suitable standard so that a relatively large quantity of trousers may be supported by this rack in such a manner that the trousers will 15 not be wrinkled and so that any desired pair or number of pairs of trousers may be removed from the rack without disturbing the other garments.

Another object of this invention is to provide an 20 improved clamping means in association with a rack for each individual pair of trousers so that a particular pair of trousers may be quickly removed from the clamping means without removing the supporting means from the display rack.

A further object of this invention is to provide 25 a spring pressed clamp for the trousers which is so constructed that release of the clamp will permit the clamp to automatically swing into a clamping position.

A still further object of this invention is to 30 provide a supporting means for the trousers' clamp and the trousers which is so constructed that it will be yieldingly maintained in operative position on the supporting standard structure in a manner whereby the trousers support may be 35 swung through a limited arc and so that the support will not readily become disengaged from the standard.

With the foregoing and other objects in view, 40 the invention will be more fully described hereinafter, and will be more particularly pointed out in the claims appended hereto.

In the drawings, wherein like symbols refer to 45 like or corresponding parts throughout the several views,

Figure 1 is a detail side elevation of a trouser 50 display rack constructed according to an embodiment of this invention.

Figure 2 is a sectional view taken on the line 2—2 of Figure 1.

Figure 3 is a fragmentary perspective view of 55 the rack.

Figure 4 is a perspective view of one of the garment hangers removed from the rack.

Referring to the drawings, the numeral 10 55 designates generally a pair of standards which

are disposed in spaced apart relation and which are connected together by a plurality of horizontally disposed connecting bars 11. The standards 10 each comprise a vertical post 12 which extends downwardly through a horizontally disposed base member 13 having downturned ends 14. The downturned ends 14 have plates 15 secured thereto which are provided with holes 16 to receive screws or the like so that the standards 10 may be fixed to a floor if desired. The post 12 10 extends through the base bar 13, as at 17, and is also provided with a foot plate 18 having holes 19 to receive securing elements in the form of screws.

The horizontal rack bars 11 are provided along 15 the upper sides thereof with a plurality of longitudinally spaced apart holes 20 for the purpose of detachably receiving trouser supporting members, generally designated as 21. The trousers supporting member 21 comprises a horizontal bar 20 22 having a horizontally disposed and right angularly related portion 23 at one end thereof which has an extension 24 disposed in parallel relation to the bar 22 but offset laterally therefrom. A hook or reverted end portion 25 is 25 integral with the extension 24 and is adapted to engage in a hole 20 of an upper horizontal rack bar 11, as shown in Figure 3. The pair of trousers is adapted to be disposed over this horizontal bar 22, as shown in Figure 3, so that the trousers will 30 dependently be supported from the bar 22. A brace or downwardly extending bar 26 extends downwardly from the outer end of the horizontal bar 22 and is provided with a vertical extension 27 terminating in an outwardly extending hook 28 35 which is adapted to engage in a hole 20 of a lower bar 11.

In order to provide a means whereby the trousers T will not become disengaged or disarranged from the supporting bar 22, I have provided 40 a releasable clamping member, generally designated at 29, which is secured to the supporting member 21. The clamping member 29 comprises a clamping bar 30 provided with an angularly disposed inner end portion 31 which is wrapped spirally about the extension 23, as at 32. This spiral portion 32 comprises a spring, one end 45 33 of which engages the offset member 24 and the other end of which is integral with the clamping 50 bar 30. The clamping bar 30 is adapted to be disposed in substantially parallel relation to the supporting bar 22 and the forward end of this bar 30 is bent inwardly, as at 34, so that the forward end of the clamping member 29 will extend 55

to the side of the supporting bar 22 opposite from the bar 30, as shown in Figures 3 and 4.

A locking member 35 is formed integral with the clamping member 29, the locking member 35 being formed by bending the forward end of the bar 30 upwardly in substantially U-shape so that the locking member 35 will normally extend above the trousers supporting bar 22. One leg of the locking member 35 is provided with an extension 36 terminating in a loop or handle 37 which extends outwardly beyond the end of the supporting bar 22 and provides a convenient lever or handle for manipulation of the clamping member 29.

15 As shown in Figures 1 and 3, the supporting rack bars 11 are so arranged that the intermediate bars 11 provide a support for the inner end of the bar 22 of one rack 21 and also provide a support for the lower hooked end 28 of an upper 20 supporting member 21. In this manner, a relatively large number of trousers supporting members may be mounted on a single rack structure without wrinkling or otherwise disfiguring the trousers while, at the same time, the trousers 25 mounted in this rack can be viewed or displayed to the greatest advantage. Preferably, the supporting members 21 have the opposite ends 25 and 28 so disposed relative to each other that the bars 22 and 26 will be placed under some tension 30 when the supporting member 21 is mounted in a pair of supporting rack bars 11.

In the use of this display rack, the bars 11 may be made of any desired length and threaded or otherwise secured in the vertical posts or standards 12 in vertically spaced apart relation. The holes 20 of the bars 11 are disposed on the upper side of each bar so that the hook members 25 and 28 may readily engage therein. In order to clamp a pair of trousers on the rack member 21, the trousers are draped over the bar 22 after the manner shown in Figure 3. At this time the clamping member 29 may be raised above the bar 22 by initially moving the bar 30 downwardly a sufficient distance so that the locking member 35 will clear the bar 22. The bar 30 may then be moved laterally or as shown in Figures 3 and 4, the bar 30 may be moved to the right and then raised above the bar 22. The bar 22 is slightly longer than the width of the trousers 50 when folded so that the locking member 35 will not contact with the trousers T. Assuming that the trousers T have been draped over the bar 22 and the clamping member 29 is in a disengaged position, the bar 30 may then be lowered so that the end portion 33 of this spring 32 will contact with the extension 24 when the bar 30 is disposed at an angle inclined upwardly to the horizontal so that when the bar 30 is swung downwardly to permit the locking member 35 to engage inside 55 the angle formed by the bar 22 and the bar 26, the bar 30 will be tensioned by the spring 32. The engagement of the locking member 35 with the bar 22 is facilitated by the sliding contact of the lever extension 36 with the side of the upper end of the bracing bar 26.

In the event it is desired to remove a pair of trousers from the rack structure without removing the trousers from the supporting member 21, this can be accomplished by forcing the hook members 25 and 28 out of the holes 20. The supporting member 21 is constructed of relatively resilient material so that the bar 26 and the bar 22 may be moved relative to each other sufficiently to accomplish the release of the hook members 25 and 28 without changing the con-

figuration of the bars 22 and 26. In order to release a pair of trousers from a supporting member 22 without removing the member 21 from the rack, it is only necessary to move the clamping member 29 downwardly against the tension of the spring 22 to a point where the holding member 35 becomes disengaged from the supporting bar 22 after which the clamping member 29 may be raised to a released position as hereinbefore described.

10 It is obvious that various changes and modifications may be made in the details of construction and design of the above specifically described embodiment of this invention without departing from the spirit thereof, such changes and modifications being restricted only by the scope of the following claims.

15 What is claimed is:

1. A garment display rack comprising a plurality of vertically spaced apart horizontal supporting bars provided with longitudinally spaced apart holes in the upper surfaces thereof, means for supporting said bars in spaced apart relation, and a plurality of garment supporting brackets 20 engaging said bars, said brackets including a substantially V-shaped supporting member provided with hooked portions at the divergent ends thereof, one side of said supporting member being disposed in substantially horizontal position, means for offsetting the hooked end of said one side of said supporting member from the longitudinal axis thereof, a clamping member swingably engaging said means for offsetting said hooked end, and a spring engaging said clamping member to constantly urge said clamping member in the direction of said one side of said supporting member.

2. A garment display means comprising a supporting means, a garment supporting bracket, means for mounting said bracket on said supporting means, said bracket comprising an elongated horizontally disposed bar, a clamping member disposed in substantially parallel relation to said bar, means at the inner end of said clamping member for swingably securing said clamping member to said bar, a spring integral with the inner end of said clamping member constantly urging said clamping member in the direction of said bar, an obliquely disposed outer end carried by said clamping member terminating on the side of said bar opposite from said clamping member, an upwardly offset locking member carried by said outer end of said clamping member, said locking member engaging the outer end of said bar when in locking position to maintain said clamping member in clamping position, and an outwardly extending arm carried by said locking member and cooperating therewith to maintain the outer end of the clamping member against lateral movement in either direction.

3. As a new article of manufacture, a garment supporting bracket comprising a substantially V-shaped member having one side thereof disposed in horizontal position, means carried by the divergent ends of said member for engagement with a supporting means to swingably secure the member to said supporting means, an elongated clamping member, a laterally offset portion carried by said horizontal side adjacent the free end thereof, means carried by said clamping member engaging said offset portion to swingably mount said clamping member on said horizontal side in a position to dispose said clamping member in substantially parallel relation to

5 said horizontal side, a spring integral with said clamping member mounting means for constantly urging said clamping member upwardly, an upwardly extending locking member carried by the outer end of said clamping member and offset laterally therefrom whereby to engage said horizontal side on the side opposite from said clamping member, and an outwardly extending arm carried by said locking member engageable with 10 the other side of said V-shaped member and cooperating with said locking member in maintaining said clamping member in clamping position.

4. A garment hanging device comprising a support, a garment receiving member carried by said support, said garment receiving member having an offset portion engaging with the support, and clamping means cooperating with said member to hold the garment thereon having a hinging 15 movement around the offset portion, and spring means coacting with said offset portion to yieldably resist the movement of the clamping means into clamping engagement with a garment on said member, said member and clamping means having 20 cooperating parts for binding the clamping means in clamping position against a garment on said member.

5. A garment hanger comprising a support, a bar for receiving a garment having an offset end portion engaged with said support, a clamping member having a hinging movement at one end about the offset portion of said bar and being coiled about the offset portion to produce a resilient hinge for normally holding the clamping member away from said bar, and locking means for binding the clamping member against a garment on said bar.

6. A garment hanger comprising a support, a horizontal bar for carrying garments having a right angular end portion constituting a shank and an offset end extension substantially parallel with said bar but offset laterally therefrom, said extension having means for engaging with said support, a clamping member of resilient material having one end portion wound in a number of convolutions about said shank and with its terminal end portion engaging said extension whereby to releasably and normally maintain said clamping member out of clamping engagement with said bar, and a locking member for engaging the free end portion of said clamping member in resilient tensioned clamping engagement with a garment upon said bar.

MALCOLM R. ROSS.
